Primary Examiner — John Windmuller*Assistant Examiner* — John R Yeh(74) *Attorney, Agent, or Firm* — MH2 Technology Law Group, LLP(57) **CLAIM**

We claim the ornamental design for an indoor parcel locker, as shown and described.

DESCRIPTION

FIG. 1 is a front, perspective view of an indoor parcel locker, according to our new design; and,

FIG. 2 is a front elevation view thereof.

The broken lines in the drawings depict portions of the indoor parcel locker that form no part of the claimed design.
